UNITED STATES PATENT OFFICE.

ERNEST GERMAIN, OF SANMAUR, QUEBEC, CANADA.

SNOW PLANE.

Application filed November 21, 1922. Serial No. 602,491.

To all whom it may concern.

Be it known that I, ERNEST GERMAIN, a subject of the King of Great Britain, residing at Sanmaur, Province of Quebec, Canada, have invented certain new and useful Improvements in Snow Planes; and I do hereby declare that the following is a full, clear, and exact description of the invention, such as will enable others skilled in the art to which it appertains to make and use the same.

The present invention pertains to a novel snow plane which is designed to travel over snow and frozen lakes and rivers or other such places that are without roads during the winter. The plane is adapted to slide from ice to water and from water to ice, will climb steep hills and operate in a fairly strong wind.

The machine is mounted on a pair of parallel forward skis and an intermediate rear ski, the latter being used as a rudder on both snow and water. The three skis are made air tight and are of sufficient buoyancy to support $1\frac{1}{4}$ times the full load of the machine. The plane, while having several properties of the hydroplane, is not designed for water and is not intended to fly in the air, although various features of this invention may be useful if applied to a hydroplane or aeroplane.

In aeroplane design lateral stability is obtained by ailerons or wing warp, the pressure of high speed air being used. In a snow plane where the speed is lower than in an aeroplane and the lateral balance is partly maintained by the contact of the skis with a solid surface, it is necessary to change the incidence of each wing in opposite directions with relation to a common axis in order to relieve some of the weight on the skis when the latter are travelling in a curved path and also to counteract the centrifugal forces acting upon the overhead parts. To this end, the invention includes a construction by means of which the two wings can be given simultaneous incidence from zero to 12 degrees on the same side of the axis, and an auxiliary device is provided for giving the wings opposite incidence ranging from 1 to 3 degrees. The simultaneous incidence above referred to is effected by a mechanism operated by a lever, and the opposite incidence is produced by

means controlled from a foot bar, both the lever and the foot bar being within the reach of the operator.

The steering of the plane depends upon the traction principle, and is similar to the steering of the boat by a rudder. This arrangement is particularly useful in a device of this character which is adapted for roadless tracts, lakes and rivers where space is vast. At the lower portion of the machine frame is supported a stationary sector having a groove in which the front end of the rear ski is received and adapted to travel. Opposite sides of the front end of the ski are connected by means of a cable to a steering wheel also within the reach of the operator. Depending on the power of the motor, the machine, with the addition of tail members and the elimination of certain features which would obviously be detrimental in aeroplane construction, can be made to fly.

The invention is fully disclosed in the following description and in the accompanying drawings in which:

Figure 1 is a front elevation of the device;

Figure 2 is a side elevation;

Figure 3 is a perspective skeleton view;

Figure 4 is a detail plan view, partly in section, of the sprocket mechanism shown at the rear end of Figure 3;

Figure 5 is a plan view of the guide plate and associated parts;

Figure 6 is a section on the line 6—6 of Figure 5;

Figure 7 is a detail elevation of the streamlined cable;

Figure 8 is a vertical section through the steering wheel and rod shown in Figure 3;

Figure 9 is a section on the line 9—9 of Figure 8;

Figure 10 is a detail plan taken on Figure 8;

Figure 11 is a front elevation of the seat;

Figure 12 is a plan view of the machine;

Figure 13 is a detail elevation of the nose, showing the shock absorber in section;

Figure 14 is a section on the line 14—14 of Figure 13;

Figure 15 is a section on the line 15—15 of Figure 13;

Figure 16 is a plan on Figure 15 with the top removed;

- Figure 17 is a vertical section of one of the bearings;
- Figure 18 is a section on the line 18—18 of Figure 17;

- Figure 20 is a section on the line 20—20 of Figure 15;
- 10 Figure 21 is a side elevation showing the skeleton of the machine;
- Figure 22 is a plan of the skeleton of the machine;
- Figure 23 is a detail of the forward portion of the machine in skeleton;
- 15 15 Figure 24 is a side elevation corresponding to Figure 23;
- Figure 25 is a detail plan view partly in section of the segment, taken on the line 25—25 of Figure 26;
- 20 20 Figure 26 is a section on the line 26—26 of Figure 25;
- Figure 27 is a front elevation corresponding to Figure 23;
- 25 Figure 28 is a detail plan view of the rear end of the machine in skeleton;
- Figure 29 is a section on the line 29—29 of Figure 28;
- 30 Figure 30 is a section on the line 30—30 of Figure 27;
- 30 Figure 31 is a section on the line 31—31 of Figure 30;
- Figure 32 is a section on the line 32—32 of Figure 27;
- 35 Figure 33 is a detail skeleton plan view of the center section and wings;
- Figure 34 is an elevation on the line 34—34 of Figure 33;
- 40 Figure 35 is a section on the line 35—35 of Figure 33;
- 40 Figure 36 is a section on the line 36—36 of Figure 33;
- Figure 37 is a front view of Figure 34; and,
- 45 Figure 38 is an enlarged section on the line 38—38 of Figure 33.
- The device is mounted on a pair of forward parallel skis 1 and an intermediate rear ski 2. Upon each of the forward skis is mounted a pair of aligned bearing members 3 (Figure 17) which are disposed slightly to the rear of the transverse axis. These bearings are preferably formed of aluminum and hollowed out as at 4 for lightness. In the top of each bearing is formed a shallow recess 5 communicating with an additional cavity 6 for the reception of a square piece of soft rubber 7 which acts as a cushioning member. The top of each rubber inset is concaved as at 8 to provide a seat for a two part bronze bushing 9. The hollow axle 10 passes through the bushings and serves as the uniting means for the two forward skis. Each bearing is equipped with a suitable cap 11 through the sides of which are passed bolts 12; these bolts also extending through
- the bearings 3 for securing them to the skis. Ringlets or collars 13 are brazed on the axle at opposite sides of the bearings for retaining the axle against shifting along its longitudinal axis and for holding the skis 70 in constant spaced relation.
- The fuselage comprises a pair of upper and lower frames 14 and 15 respectively which converge to a point at the rear end. A strip 16 is extended across the sides of 75 the lower frame and supports a king bolt 17 which passes into the rear ski 2 as shown in Figure 2, a suitable bearing 18 being interposed to afford pivotal connection between the fuselage and the rear ski. Between the bearings 3 and each end of the axle is mounted an inverted U-shaped fitting or union 19 from the back of which extends an angular web 20. Each such web has fixed to its inner face a socket 21 which receives a strut 22 extending longitudinally of the machine and secured to the lower plane 15 as indicated in Figure 28. These two struts form with the forward axle 10 a triangle in which the body or fuselage is 80 mounted. The ends of the webs are formed with sockets 23 which receive the legs of upwardly extending V's 24 on the upper ends of which is mounted a miniature fuselage or center section 25. This center section is constructed of a plurality of longérons 26 and suitable spacers 27 (Figure 34) over which a suitable covering fabric is drawn. To the forward ends of the lower longérons is secured a pair of engine bearings 27' on which is mounted an air cooled motor 28. The interior of the center section is designed to contain a gasoline tank 29 and oil tank 29', as shown in Figures 33 and 34. The motor shaft 128 is inclined at an angle 95 of three degrees to the horizontal, thus giving the line of thrust an upward grade of 3 degrees and the propeller 129 is fixed at right angles thereto.
- The axle 10 is formed in two sections, the inner contacting ends of which are surrounded by a sleeve member 30 (Figures 27 and 32) which is secured to the sections by pins 31 penetrating therethrough. On the upper part of the sleeve is formed an eyelet 32 which is engaged on opposite sides by the legs of a center V 33 which are bound by a bolt 34. The upper ends of the legs of the V 33 are secured to opposite sides of the center section, thus providing additional supporting means for the latter, as shown in Figure 1.
- The forward portion of the fuselage is completed by a pair of front posts 35 (Figure 21) which join the forward ends 110 of the upper and lower frames. The lower ends of these posts carry aluminum brackets 36 which receive the axle 10 whereby the front end is supported. A nose portion 37 extends outwardly from the forward 115
- 120
- 125
- 130
- 135

ends of the frames and consists of two angular members 38 composed of square tubing. The vertices of these members are reinforced by angle plates 38', 39 through 5 which is passed a fastening bolt 40.

A wing supporting axle 41 passes transversely through the body of the center section, being supported in bearings 42 formed in a pair of opposite spacers 27, as 10 shown in Figures 34 and 35. The wings are of a semi-cantilever construction consisting of rigid panels each made of five parallel spars 43 of spruce $\frac{1}{8}$ of an inch thick which are traversed by spaced ribs 44 15 parallel thereto. The ribs are inlaid into the spars as in Figure 38, and the vertical spaces thus formed are filled with webs 45 forming an I-beam cross section. The master ribs 46 are engaged by parallel web members 45' at opposite edges whereby a 20 box like construction is formed. The spars are pierced for the passage of the internal bracing wires 47, while the webs are perforated as at 48 for lightening. The central spar is about 6 inches in width and the 25 remaining spars are of decreasing widths whereby a stream line cross section is developed, as shown in Figure 36. The panels are built on special forms and are covered with aero cloth after being fastened together. The axle 41 carries clips 49 in line with the intermediate master ribs for receiving the upper ends of wing supporting tubes 50, the lower ends of these tubes being 30 received in sockets 51 (Figures 30, 31) clamped to the webs 20 by the same bolts 52 that hold the above mentioned sockets 21. The clamps are joined to the forward ends of the engine bearers by cables 53 for 35 relieving drag stresses. Steel envelopes 54 are passed around the intermediate master ribs at opposite sides of the clips 49 and serve to receive the outer ends of the control cables 55, the operating mechanism for 40 which is described below.

The sides of the lower frame 15 are joined by cross bars 56 and 57 at the front and rear ends respectively, as shown in Figure 3. These bars support the ends of 45 spaced guide strips 58 between which is received a slidable control board 59. A rack 60 is formed intermediate the ends of the control board and is engaged by a pinion 61 mounted on a shaft 62 supported in bearings 63 on the sides of the lower frame. On one of the bearings is formed a twelve toothed quadrant 64, while adjacent thereto is an operating or control lever 65 keyed 50 to the shaft 62 and carrying a grip 66 adapted to engage the teeth of the quadrant. An intermediate cross bar 67 extends across the lower frame and beneath the guide strips. A perforated plate 68 is secured to the guide strips by means of U-bolts 69 55 passing therethrough and under the bar

67. The forward end of the control board extends through and beyond the forward bar 56 where it is provided with a mounting 70 on which is pivoted a double sectional segment 71 which is cast of aluminum. Opposed bearing strips 72 are placed at opposite sides of this member each being supported by an end of the board 56 and one of the posts 35 for receiving the guide pulleys 73. The back of each of the U- 75 plates 19 (Figures 30 and 31) has secured thereto a pair of brackets 74 by which are supported additional pulleys 75. The cables 55 extending from the wings pass over the pulleys 75 and 73, intersecting at 80 the sides of the member 71 and secured to opposite ends of said sides, as in Figure 25. The control board carries an additional mounting 76 on which is pivoted a foot bar 77 provided at its ends with foot straps 85 (not shown). Through the opposite sides of the member 71 are passed clevises 78 which are connected to the ends of the foot bar by means of cords 79. At the rear end of the control board is mounted a pair of legs 80 which support the operator's seat 81. When the control lever 65 is pulled rearwardly, the control board is moved forwardly carrying the element 71 with it, and the operator's seat is guided by parallel 90 rails 81' (Figures 21, 22) fixed to the frame of the fuselage. Consequently the foremost of the cables 75 are slackened, while the remaining two cables are tightened, thus causing an equal upward tilting of both 95 wings. Obviously a reverse movement of the lever will result in opposite movement of the wings. This device is employed for imparting equal and simultaneous change to 100 both wings.

At the rear end of the control board is disposed still another block 82 (Figures 21, 22) on which is rotatably supported a sprocket wheel 83, a portion 84 of which (Figure 4) is blank. In the base of the 105 rear leg 80 is mounted a bushing 85 through which a pin 86 is adapted to slide, this pin being normally urged outwardly by a spring 87 in the bushing. The pin is adapted to engage in a notch 88 formed in the blank 110 portion 84 for the purpose of holding the sprocket against unintentional or undesired rotation. The sprocket is engaged by a roller chain 89 the ends of which are joined to the ends of the foot bar by means of 115 cords 90. When one end of the foot bar is pushed inwardly, the corresponding side of the sectoral member 71 advances, while the other side moves rearwardly about the pivot point. Accordingly the forward cable 55 connected to one of the wings is tightened 120 and the other forward cable is slackened, the remaining cables also taking opposite movements. This results in one of the wings being turned upwardly, while the 125 130

other is tilted downwardly, as distinguished from the action previously described resulting from the operation of the lever 65. The incidence obtained from the lever 55 varies from zero to 12 degrees, and the quadrant 64 contains twelve teeth, one for each degree. The wings can be tilted 3 degrees on each side of the central tube 41 by means of the foot bar. For a left turn 10 of the snow plane, the pivot bar is operated in the direction of the turn, which action increases the incidence of the right wing and reduces the left by a similar amount. If the plane is travelling over hard snow 15 and if the lever 65 is maintained in the second notch, giving the wings an equal incidence of 2 degrees, the right hand wing will rise 3 degrees, increasing the angle thereof to 5 degrees, while the left hand wing falls 3 degrees and attains an incidence of 1 degree negative.

The steering mechanism for the rear ski comprises a sector 91 fixed beneath the body, being preferably secured to the lower frame 23 15, as shown in Figure 21. The sector is covered with a stream line sheeting 92 for decreasing air resistance. The forward end of the rear ski is fitted with a reinforcing member 93 which terminates in a lip 94 beneath which is secured an angle iron 95. The rear edge of the sector is notched or stepped, as at 96 (Figure 29), the base of the step being provided with a cover plate 97. The lip 94 is received in the notch and 30 is adapted to slide therein substantially throughout the length of the sector. At the ends of the sector are provided links 98 for supporting pulleys 99. An additional pair of guide pulleys 100 is supported on angle 40 plates 101 secured to the intersections between the lower frame 15 and the cross bar 57. On the lower frame is erected a standard 103 (Figure 3) in which is journaled a steering rod 104 surrounded by a steering 45 post 105 at the outer end of which is fixed a steering wheel 106. The post is slideable with relation to the rod and has formed therethrough opposite longitudinal slots 107 which receive a pin 108 passed through 50 the steering rod. By this arrangement the post is slideable but not rotatable with relation to the rod so that the wheel 106 may be adjusted longitudinally of the frame in accordance with the movement of the seat 55 81. To the inner end of the steering rod is fixed a drum 109 around which is wound a cable 110, this cable passing over the pulleys 99 and 100 and also over additional guide pulleys 111 and 112 journaled at opposite sides of the standard 103. The ends 60 of the cable are secured to eyes 93' formed at opposite sides of the member 93 at the forward end of the rear ski. Obviously upon rotation of the wheel 106 in either 65 direction, one side of the cable 110 is pulled

upwardly over the pulleys whereby the forward end of the rear ski is caused to travel along the sector 91 to steer the plane.

An additional tube 113 is laid across the forward skis in parallel relation to the axle 70 10. Semi-diagonals 114 slope upwardly from the vertices of the rectangle thus formed and have their inner ends attached to a rectangular plate 115 (Figure 16). This plate is disposed within the fuselage, 75 as shown in Figure 24, and works back and forth when the skis are violently struck. This plate is cushioned upon a thick piece of rubber 116 laid across the lower sides of the angles 37. Beneath the lower legs of 80 the angles is laid an under plate 117 of metal similar to the plate 115 and rounded pieces of hard wood 118 are secured to each of the last mentioned plates, the lower piece 118 and the under plate being fixed to the angles 85 by means of bolts 119, as shown in Figure 15. The entire mass is held together by means of a rope 120 wound spirally there-around to allow separation between the angles and the rubber piece 116. A flexible 90 member 121 is anchored beneath the plate 115 and passes therethrough to the piston rod 123 of a piston 122 slidably mounted in an air cylinder 124 fixed to the upper legs of the angles. The back of the piston is 95 joined to the base of the cylinder by means of a spring 125 which facilitates rearward or upper movement of the piston upon corresponding yielding of the rubber piece 116. In the front wall of the cylinder is provided 100 a check valve 126 and a restricted air outlet 127. When the device 115-120 expands, the piston 122 is drawn rearwardly and the space at the forward side is readily filled by air passing through the inwardly 105 opening check valve 126 and the air passage 127. When the movement is reversed, the return of the piston is retarded because of the check valve being closed and the passage 127 being of restricted size. Accordingly, the piston and cylinder act as a 110 shock absorber.

The skis are each built of six longitudinal rock elm members 130 (Figure 27) which are reinforced by blocks 131 in the vicinity 115 of the bearing members 3. These members are connected horizontally and vertically by means of mahogany braces 132. At intervals, perforated rectangular plates 133 are fixed within the longitudinal members to 120 provide additional bracing means. The outside is preferably formed of two ply cross grain covering of cedar from the center of the sides and around the top, and cedar and beech from the center of the 125 sides and around the bottom. The lining 134 under the convex of the ski is removable, being held in place by screws (not shown).

A preferred embodiment of the inven- 130

tion has the following dimensions: Span, 18' 4"; wing ratio, 4; length overall, 18' 6"; height, 6' 2"; front skis, 9' long by 14" wide; maximum height, 14"; rear ski, 5 9' long by 10" wide; height 12".

A machine constructed according to these dimensions has a weight of about 600 pounds, and the center of resistance lies close to the ground due to the friction of

- 10 the skis. The center of lift is directly over the points of attachment of the front skis, and the center of gravity is approximately 2' behind the center of lift, thus enabling the machine to rise over the snow 15 and to counteract the difference between the forces of thrust and resistance. The center of buoyancy is 1' ahead of the center of lift. The propeller is 6' 6" in diameter by 4' 6" pitch and its tips clear the 20 ground by 28" in order to avoid striking snow drifts.

Having thus fully described the invention, what I claim as new and desire to protect by Letters Patent is:—

- 25 1. A plane comprising a forward pair of parallel skis, an axle extending thereacross and journaled therein, a rear ski intermediate said forward skis, a fuselage hingedly connected to said axle and pivotally connected to the rear ski, a pair of V's 30 extending upwardly from the ends of the axle, and a center section supported by said V's.

- 35 2. A plane comprising a forward pair of parallel skis, an axle extending thereacross and journaled therein, a rear ski intermediate said forward skis, a fuselage hingedly connected to said axle and pivotally connected to the rear ski, a pair of V's 40 extending upwardly from the ends of the axle, a center section supported by said V's, and a motor and propeller disposed in advance of said center section.

- 45 3. A plane comprising a forward pair of parallel skis, an axle extending thereacross and journaled therein, a rear ski intermediate said forward skis, a fuselage hingedly connected to said axle and pivotally connected to the rear ski, a pair of V's 50 extending upwardly from the ends of the axle, a center section supported by said V's, a wing axle extending transversely through said center section, wings supported on said axle at opposite sides of the section, and 55 means for tilting said wings.

- 60 4. A plane comprising a forward pair of parallel skis, an axle extending thereacross and journaled therein, a rear ski intermediate said forward skis, a fuselage hingedly connected to said axle and pivotally connected to the rear ski, a pair of V's 65 extending upwardly from the ends of the axle, a center section supported by said V's, a wing axle extending transversely through 68 said center section, wings supported on said

axle at opposite sides of the section, means for tilting said wings, and a motor and propeller mounted in advance of said center section.

5. A plane comprising a pair of parallel 70 forward skis and an intermediate rear ski, a body supported on the front skis and pivoted to the rear ski, a sector carried by the body and adapted to guide the forward edge of the rear ski, and means for turning 75 said rear ski on its pivot.

6. A plane comprising a frame and a pair of wings supported thereby, a pair of guide strips extending longitudinally of said frame, a control board slidably mounted between said strips, a block pivoted to said control board, and a pair of cables extending from each end of said block to one of 80 said wings.

7. A plane comprising a frame and a pair 85 of wings supported thereby, a pair of guide strips extending longitudinally of said frame, a control board slidably mounted between said strips, a block secured to said control board, a pair of cables extending 90 from each end of said block to one of said wings, a rack formed in the upper face of said control board, a shaft extending transversely of the frame and carrying a pinion meshing with said rack, and means for 95 rotating said shaft.

8. A plane comprising a frame and a pair 100 of wings supported thereby, a pair of guide strips extending longitudinally of said frame, a control board slidably mounted between said strips, a block secured to said control board, a pair of cables extending from each end of said block to one of said wings, a rack formed in the upper face 105 of said control board, a shaft extending transversely of the frame and carrying a pinion meshing with said rack, a toothed quadrant disposed at one end of the shaft, and a control lever keyed to the shaft and adapted for selective engagement with said 110 quadrant.

9. A plane comprising a frame and a pair 115 of wings supported thereby, a pair of guide strips extending longitudinally of said frame, a control board slidably mounted between said strips, a block secured to said control board, a pair of cables extending from each end of said block to one of said wings, a rack formed in the upper face of said control board, a shaft extending transversely of the frame and carrying a pinion meshing with said rack, a toothed quadrant disposed at one end of the shaft, a control lever keyed to the shaft and adapted for selective engagement with said 120 quadrant, and an operator's seat mounted on the control board in proximity to said lever.

10. A plane comprising a frame and 125 wings supported thereby at opposite sides 130

thereof, a block pivotally and slidably mounted in the frame, and a pair of cables extending from each end of the block to one of the wings.

11. A plane comprising a frame and wings disposed at opposite sides thereof, a pair of guide strips extending longitudinally of said frame, a control board slidable between said strips, a block pivoted to said strips, a pair of cables extending from each end of said block to one of the wings, and means for sliding said board.

12. A plane comprising a frame and wings disposed at opposite sides thereof, a pair of guide strips extending longitudinally of said frame, a control board slidable between said strips, a block pivoted to said strips, a pair of cables extending from each end of said block to one of the wings, means for sliding said board, a foot bar pivoted to the board, and cords connecting opposite ends of said bar to opposite ends of the block.

13. A plane comprising a frame and wings disposed at opposite sides thereof, a pair of guide strips extending longitudinally of said frame, a control board slidable between said strips, a block pivoted to said strips, a pair of cables extending from each end of said block to one of the wings, a rack formed in the upper face of said board, a shaft extending transversely of the frame and carrying a pinion adapted to mesh with the rack, and means for turning the shaft.

14. A plane comprising a frame and wings disposed at opposite sides thereof, a pair of guide strips extending longitudinally of said frame, a control board slidable between said strips, a block pivoted to said strips, a pair of cables extending from each end of said block to one of the wings, a rack formed in the upper face of said board, a shaft extending transversely of the frame and carrying a pinion adapted to mesh with the rack, means for turning the shaft, a foot bar pivoted to the board, and cords connecting opposite ends of the bar to opposite ends of the block.

15. A plane comprising a frame and wings disposed at opposite sides thereof, a pair of guide strips extending longitudinally of said frame, a control board slidable between said strips, a block pivoted to said strips, a pair of cables extending from each end of said block to one of the wings, a rack formed in the upper face of the board, a shaft extending transversely of the frame and carrying a pinion adapted to mesh with the rack, a toothed quadrant at one end of the shaft, a lever keyed to the shaft and adapted for selective engagement with the quadrant, an operator's seat mounted on the board in proximity to said

lever, a foot bar pivoted to the board in proximity to the seat, and cords connecting opposite ends of said bar to opposite ends of the block.

16. A plane comprising a frame, a rear ski pivoted to the bottom thereof, a sector supported by the frame and having a groove formed along its arc of less radius, a lip formed on the forward end of the rear ski and received in said groove, and means for moving said lip along the groove.

17. A plane comprising a frame, a rear ski pivoted to the bottom thereof, a sector supported by the frame and having a groove formed along its arc of less radius, a lip formed on the forward end of the rear ski and received in said groove, a standard mounted on the frame, a steering rod journaled in the standard, a drum fixed to the rod, and a cable having its intermediate portion wound around the drum and its ends secured to opposite sides of the rear ski.

18. A plane comprising a frame, a rear ski pivoted to the bottom thereof, a sector supported by the frame and having a groove formed along its arc of less radius, a lip formed on the forward end of the rear ski and received in said groove, a standard supported on the frame, a steering rod journaled in the standard, a drum secured to the rod, pulleys carried by the standard and by the ends of the sector, and a cable having its intermediate portion wound around the drum, said cable being passed over said pulleys and having its ends connected to opposite sides of the rear ski.

19. A plane comprising a frame, a rear ski pivoted to the bottom thereof, a sector supported by the frame and having a groove formed along its arc of less radius, a lip formed on the forward end of the rear ski and received in said groove, means for moving said lip along the groove, a pair of wings supported by the frame, a block slidably mounted on the frame, and a pair of cables extending from each end of said block to one of said wings.

20. A plane comprising a frame, a rear ski pivoted to the bottom thereof, a sector supported by the frame and having a groove formed along its arc of less radius, a lip formed on the forward end of the rear ski and received in said groove, means for moving said lip along the groove, a pair of wings supported by the frame, a block pivotally mounted on the frame, and a pair of cables extending from each end of said block to one of said wings.

21. A plane comprising a frame, a rear ski pivoted to the bottom thereof, a sector supported by the frame and having a groove formed along its arc of less radius, a lip formed on the forward end of the rear ski and received in said groove, means

for moving said lip along the groove, a pair of wings supported by the frame, a block slidably and pivotally mounted on the frame, and a pair of cables extending from each end of said block to one of said wings. 15

22. A plane comprising a frame, a rear ski pivoted to the bottom thereof, a sector supported by the frame and having a groove formed along its arc of less radius, 10 a lip formed on the forward end of the rear ski and received in said groove, means for moving said lip along the groove, a pair of wings supported by the frame, a pair of guide rails extending longitudinally of the frame, a control board slidable between the guide rails, a block pivoted to said board, a pair of cables extending from each end of the block to one of the wings, means for shifting said board, and a seat mounted upon the board. 20

In witness whereof I have hereunto set my hand.

ERNEST GERMAIN.
